UNITED STATES PATENT OFFICE.

ELIAS HYMAN, OF NEW YORK, N. Y.

REVERSIBLE FOLDED STAIR COVERING.

Application filed June 2, 1925. Serial No. 34,310.

This invention relates to improvements in stair covering pads, particularly tread pads as they are, for instance, described in my Patent No. 1,521,153, issued December 30, 1924, and it is the principal object of my invention to provide pads of a suitable tread material, which is framed in a metal frame and which can readily be bent to follow the contour of the stairs on which the pads are 10 to be fastened in consecutive order, so as to present the appearance of a continuous length of carpet.

Another object of the invention is the provision of a pad having a central cushioned 15 member and two lateral members possessing sufficient rigidity to hold the cushioning member properly extended over a step, while being sufficiently flexible to permit bending, so as to follow the contour of the steps.

20 A further object of the invention is the provision of a stair pad having a stiffening member therein which may be of a waterproof material.

A still further object of the invention is 25 the provision of a pad having a bottom or base of rubber, or the like.

For further comprehension of the invention, and of the objects and advantages thereof, reference will be had to the following 30 description and appended claim in which the various novel features of the invention are more specifically defined.

In the accompanying drawing, forming a material part of this disclosure:

35 Fig. 1 is a top plan view of a stair pad constructed according to my invention.

Fig. 2 is a bottom plan view thereof.

Fig. 3 is a sectional side elevation of part 40 of a staircase covered by pads made in accordance with my invention.

Fig. 4 is a section on line 4—4 of Figure 1.

The individual pads constituting my improved stair covering, comprise each a pad 10 within a metal frame 11. The pad is 45 made of any well known carpet material and has an approximately, centrally located cushioned element 12, on a ground element 13, of suitable material, and a base element 14 which may be made of rubber, or the like, 50 flexible and waterproof material.

Between the elements 13 and 14, a stiffening member 15, of thin sheet metal, or other suitable, flexible material, is interposed, and this member 15 is of frame shape, but of 55 smaller size than frame 11, as shown on the drawing. When the pads are fastened to

stairs, etc., the nails 22, or the like are driven through this reinforcing member, shown on the drawing, and not through the frame 11, as is customary. I have discovered that if 60 the nails are driven through the frame 11, deformation will result, due to the accidental striking, and other causes, and therefore the contact between the frame 11, and the stairs proper is such that dirt can work its way 65 under the pad. But driving the nails within the frame, and through the reinforcement 15 serves to press 14 against the stairs proper, abutting a reaction due to the action of the bottom of the said frame 11, which 70 is, of course, adjacently below the part 14, and this forms a tight and satisfactory joint. The pad has a line of blind stitches 16 to allow a ready fastening of the pad along this line, to fit against the stair-case 17. 75

The ends of elements 13 and 14, and member 15, are held together by the metal frame 11 in the manner illustrated in Figure 4.

It is to be understood that my stair covering may be used reversed and while I have 80 shown and described the preferred form of my invention, such changes may be made, as fall within the scope of the appended claim without departure from the spirit of the invention. 85

Having thus described my invention, what I claim as new, and desire to secure by Letters Patent, is as follows:

In a stair covering, a mat comprising a base element preferably of rubber, a ground element superimposed over said base element, a stiffening frame of dimensions less than the dimensions of said mat disposed between said ground and base elements, an upper covering preferably comprising carpet material disposed over said ground element, a cushion disposed between said upper covering and said ground element positioned centrally and extended transversely of said mat, said cushion being substantially the width of the horizontal surface of a step, a metal frame of U-shaped cross section disposed around the edges of said mat, adapted to clamp the edge portions of said base, ground and covering elements together, said mat being adapted to cover the upper riser, encircle the nosing and cover the upper section of the lower rises of said stair. 100 105

In testimony whereof I have affixed my signature.

ELIAS HYMAN.
